WEINGER ROLL STOP MECHANISM

Vernon E. Dunn, Alliance, Ohio

Application January 2, 1937, Serial No. 118,783

1 Claim. (Cl. 68—253)

This invention relates to wringers for domestic washing machines and particularly to that part of the wringer mechanism which stops rotation of the rolls when pressure is released.

Experience with domestic wringers has proven that, when accidents occur, it is highly desirable to stop rotation of the rolls because continued rotation causes serious damage to garments and more serious injuries to the operator, when caught.

The particular object of this invention is to provide mechanism coacting with the roll pressure means whereby rotation of the rolls is stopped when roll pressure is released.

Another object is to provide a roll stop mechanism almost wholly contained in the gear head of the wringer so as to make possible the application of this mechanism to other kinds and types of wringers.

Other objects and benefits will be disclosed in the following description and drawings in which:

Fig. 1 is a front elevation of a wringer embodying my roll stop mechanism with one end of the wringer case and most of the wringer head broken away to the longitudinal center line to better disclose the arrangement of the interior parts;

Fig. 2 is a sectional end elevation view on the section lines 2—2, Fig. 1, showing the pressure handle in released position in its relation with the clutch cam and cam dog in stopped position.

Fig. 3 is a sectional end elevation view on the section lines 2—2, Fig. 1, the same as Fig. 2, except that the pressure handle is now in pressure application position and the clutch cam has been forced into engaged position.

Fig. 4 is a partial sectional end elevation view on the section line 4—4, Fig. 1, showing the rolls and pressure mechanism in pressure relation;

Fig. 5 is a similar sectional end elevation view, the same as Fig. 4 except that the rolls and mechanism are in released relation but ready to apply roll pressure corresponding to Fig. 3;

Fig. 6 is a broken cross sectional side elevation of the full plate and tapered point lock bar as shown in position of Fig. 4;

Fig. 7 is an enlarged side elevation, partially in cross section, showing the arrangement of the dog latch and cam arm in locked relation;

Fig. 8 is the same view as Fig. 7 except that it shows the dog latch moved out of latching engagement with the cam arm by upward movement of the wringer roll and slotted bearing bracket;

Fig. 9 is a broken, side elevation view of the wringer and head with exterior parts broken away

to show the resultant action of the mechanism when the upper roll has been released upward, the driven gear disengaged and the roll stopped;

Fig. 10 is an enlarged detailed cross sectional view of the drive mechanism between the roll and bevel gear showing the parts in drive relation;

Fig. 11 is a similar view to Fig. 10 showing the drive gear disengaged and the roll stopped; and

Fig. 12 is a small broken back elevation view of the wringer head showing the pressure handle in relation to the pressure shaft.

Now referring to Fig. 1, I designate the main frame of the wringer by the numeral 10. It will be noted that the wringer frame and head are integral, a sub-head gear case 15 being mounted in the head portion of the combined wringer frame and head 10.

The top frame 11, carrying bearing bosses 22 for the upper roll 13, has a conventional release mechanism 14 retracting tapered latch bars 20 and is slidable vertically in the main frame 10.

The lower frame 10 carries the lower roll 12 by stationary bearings, one cast in portion 10 located in outside end of wringer and one located in cast portion 10' of frame 10 between the end of the roll 12 and the drive mechanism. Bearing bracket 36 houses cams 41 and 42, as well as drive tube 37. Bracket 36 and sub-gear case are bolted together as shown in Fig. 1 with round head screws. This assembly is then bolted to 10 with four screws a, Fig. 1. Only one of the screws is shown.

Attached to the lever 28 are end plates 21 held in vertical alignment by the guide block 10' and the slotted opening 32' about the shoulder rivet 32. See Fig. 4.

These end plates are attachable to the top frame by means of the tapered end latch bars 20, the tapers 20' on the bars bearing in the taper faces 33' of the slot 33. See Fig. 6.

The sub-gear case head 15 mounts the vertical drive shaft 15' which has a conventional reversible drive mechanism including the clutch pinions 17 and 18 rotatably mounted on the drive shaft and a clutch member 16 slidably keyed to the shaft.

The handle 49 through conventional mechanism controls the forward, reverse and neutral positions of the clutch 16.

The driven gear 19 departs from conventional structure in that instead of being mounted stationary, it is slidable horizontally. The connector sleeve 37 has a slot 37' in its inner end through which the gear 19 is slidably keyed by the pin 38. See Figs. 11 and 12. The opposite end of

the sleeve drives the roll 12 through the pin 12' as shown.

A spring 39 is tensioned between the pin 38 and a button 40 to urge the gear 19 out of mesh with the gears 17 and 18.

Interposed between the gear 19 and the cam 41 is a mating cam 42 slidably keyed to the cap 36 by dual key bosses 42' in the slots 36'. When the cam 41 is rotated the cams ride up on their 10 incline faces and abut each other on the flat points of the cam faces forcing the gear 19 into driving relation with the gears 17 and 18 as shown in Fig. 1. Reverse rotation of the cam 41 allows them to mesh with each other and permits the gear 19 to be drawn out of mesh as 15 shown in Fig. 9.

Now referring to Figs. 2, 3, 4 and 5, a handle 26 is pinned to a horizontal crank shaft 27 extending longitudinally and pivotally mounted in the wringer frame 10. The handle 26 has a lever lip 26' on its inner end adapted to contact the cam arm 41' of the cam 41 and rotate it to engaged position as shown in Figs. 2 and 3. It will also be noted that the dog 23 is actuated 25 behind the vertical face of the cam wing 41 to lock cam 41 in operating position as shown in Fig. 3.

The action of spring 25 to rotate cam 41 into stopped position is well illustrated in Figs. 3 and 30 2.

Now referring to Figs. 4, 5 and 6, the crank portions 27' of the shaft 27 are shown as they engage in slots 28' of dual lever member 28 pivoted on pins 29 in the end plates 21. The opposite ends 35 of the levers 28 bear against spring plugs 30 by the adjustable set screws 29' and are urged downward by compression springs 31 mounted in each end of the wringer.

Referring to Figs. 3 and 5, the handle 26 has 40 been pulled down, the cam 41 rotated into locked operating position, the end plates 21 have been lifted up until the latch bars 20 have engaged their tapered ends 20' into contact with the taper faces 33' of the slots 33 by means of movement of 45 the levers 28 by the cranks 27' in the slots 28'. Now, by pulling the handle 26 upward, the crank 27' pulls down the top frame 11 and the roll 13 against the roll 12 by reaction of the set screw 29' against the plug 30 and the spring 31 and we 50 have the rolls in pressure relation as shown in Fig. 4.

It will readily be understood that when the pressure release mechanism is actuated, the lock bars 20 will be readily retractable because of the 55 taper contacts to release the end plates 21 allowing the upper frame and roll to move upward into released position.

Now referring to Figs. 7 and 8, it will be noted 60 that the roll 12 is restricted to a low position and from shifting sidewise by the rivet 21' as shown in Fig. 7. In this position the slot 22' in the bearing block 22 has forced the tail of the dog 23 behind the fan arm of the cam 41 which retains the driving gears in mesh. However, 65 when the roll pressure is released and the roll 12 moves upward as shown in Fig. 8, the upward movement of the slot 22' with the spring 24,

pivots the dog 23 in its mounting 23' which releases the tail from behind the fan arm 41 which permits the spring 25, as shown in Figs. 2 and 3, to rotate the cam 41 permitting the spring 39 as shown in Figs. 11 and 12 to pull the gear 19 out of mesh with the gears 17 and 18, thus stopping the rolls.

Operation

Having thus described the parts and their relation to each other, I will now describe the operation of my roll stop mechanism.

Assuming the wringer in operation, as shown in Fig. 1, the roll pressure is instantly released by the operator's touching the release target 14 15 which retracts the lock bars 20 permitting the top frame and roll to move upward to release position.

The upward movement of the roll bearing bracket 22 actuates the dog 23 into release position permitting the cam 41 to be rotated into position to mesh with cam 42 and allowing the driven gear 19 to be withdrawn from driven relationship with the horizontal wringer head gears. Thus the rotation of the rolls is stopped with release of pressure.

The wringer is again put in operating condition by holding the top frame down while the hand lever 26 is depressed. This raises the end plates 21 which re-engages the lock bars 20 into locked 30 relation with the end plates. The hand lever 26 is now raised and this pulls down the top frame and top roll into locked pressure contact with the lower roll through rotation of the cranks 27' which pivots the levers 28 against the springs 31. 35

Simultaneously with the above operation the pressure lever 26 by contact of the lever arm 26' with cam arm 41' has rotated the cam 41 to cause the drive gears to be meshed in driving relation and the downward movement of the bearing block 22 has forced the dog 23 into holding 40 position behind the fan arm of 41. Thus the rolls are in pressure relation and the wringer is in operating position.

The foregoing will, I believe, completely disclose my roll stop mechanism. I have shown and described a preferred embodiment of my invention. However I do not desire to be limited to the structure shown except by the claim thereon.

I now claim as new:

In a power driven clothes wringer, a manually 50 reversible gear head, lower and upper frames, a pair of cooperative pressure rolls in the lower frame, pressure springs in the lower frame, bail means for joining the frames together in pressure sustaining relationship, lever means in the lower frame coacting with said springs and bail to create roll pressure, safety release mechanism in the upper frame to unhook bail and release roll pressure, cam means co-axial with the driven gear to slide said gear into or out of engagement with the reversing gears in the head and cam latch means on the bail operable by upward release movement of the upper roll to permit reverse movement of the cam and disengagement 55 of the gear to stop rotation of the rolls.

VERNON E. DUNN.
